SWITCH COVER AND WIRE CONDUIT UNIT FOR A WASTE DISPOSER

James H. Enright and Charles A. Wicke, Racine, Wis.,
assignors to In-Sink-Erator Manufacturing Company,
Racine, Wis., a corporation of Wisconsin

Filed Dec. 12, 1966, Ser. No. 4,996

Term of patent 14 years

(Cl. D55—1)

FIG. 1 is a perspective view of a switch cover and wire conduit unit for a waste disposer embodying the present invention as applied to a waste disposer.

FIG. 2 is a side elevational view of the unit.

FIG. 3 is a top plan view thereof.

FIG. 4 is a cross section taken along line 4—4 of FIG. 2.

FIG. 5 is a cross section taken along line 5—5 of FIG. 2.

The broken line showing is for illustrative purposes only.

We claim:

The ornamental design for a switch cover and wire conduit unit for a waste disposer, as shown and described.
